Packaging Corporation, New York, N.Y., a corporation of Virginia

Filed Oct. 15, 1963, Ser. No. 76,988

Term of patent 14 years

(Cl. D34—13)

FIG. 1

FIG. 2

FIG. 3

FIGURE 1 illustrates the face cards for the suit of diamonds of a deck of playing cards, showing my new design; and

FIGURE 4 illustrates the face cards for the suit of hearts; and

The ornamentation upon the faces of the cards is the dominant feature of the design, the remaining cards of the deck being substantially conventional.

I claim:

The ornamental design for a deck of playing cards, as shown and described.
